UNITED STATES PATENT OFFICE.

CHARLES W. LEGUILLOON, OF AKRON, OHIO, ASSIGNOR TO THE B. F. GOODRICH COMPANY, OF NEW YORK, N. Y., A CORPORATION OF NEW YORK.

APPARATUS FOR MAKING GROMMETS.

Application filed July 5, 1924. Serial No. 724,446.

This invention relates to endless rings such as are used, for example, as reinforcements in the beads of straight-side pneumatic tires, and to methods and apparatus for making the same.

My chief objects are to provide an improved ring consisting of a winding of strip material having its convolutions securely anchored to each other, and to provide improved economical procedure and apparatus for making such rings. More specific objects are to provide for concurrently winding a plurality of such rings, for quickly binding the convolutions of each ring together while they are on the winding form, and for easily and quickly removing them therefrom. A further more specific object is to provide a stapling device adapted to be readily and accurately positioned upon a winding drum to clinch a staple about a ring-structure wound on said drum.

Of the accompanying drawings:

Fig. 1 is a front elevation of apparatus embodying and adapted to carry out my invention in its preferred form.

Fig. 2 is a fragmentary section of the winding form or drum, on a large scale, showing means for anchoring to the drum the leading end of the strip to be wound.

Fig. 3 is a section on line 3—3 of Fig. 1.

Fig. 4 is a front elevation of part of the apparatus shown in Fig. 1, showing the method of severing the strip material from the finished work.

Fig. 5 is a fragmentary perspective view of the drum upon which the rings are built, showing the method and apparatus for binding the ends of the winding.

Fig. 6 is a fragmentary section through the drum and work at the point where the binding means is applied.

Fig. 7 is a front elevation of the building drum, collapsed to permit removal of the finished work.

Fig. 8 is a fragmentary perspective view of the finished work.

Referring to the drawings, 10, 10 are a pair of floor brackets or standards for the winding apparatus, 11 is an auxiliary frame adjacent thereto upon which is mounted timing mechanism for stopping the drive of the winding apparatus at the end of each operation, and 12 is another auxiliary support or frame upon which is mounted guiding and feeding means for a plurality of parallel

ring-forming strips 13. Each of the strips 13 as here shown consists of a continuous, flat, tape-like structure or woven or braided wire substantially embedded in a tacky rubber compound, the strip preferably being treated with a solvent as it approaches the winding mechanism, to assure good adhesion between the successive turns of the winding.

Journalized in the frames 10 is a horizontally projecting shaft 14, on the overhanging front end of which is secured a hollow, segmental, collapsible drum 15, the latter comprising an arcuate section 15^a formed with an integral radial web 16 and hub 17 arcuate sections 15^b, 15^b hinged at 18, 18 to the respective ends of the section 15^a, and a radially movable, arcuate section 15^c. The outer face of the drum is formed with a plurality of parallel, circumferential, square-section grooves 19, 19 of slightly greater width than the strips 13, and of sufficient depth to accommodate a plurality of convolutions of the latter.

Secured to and extending inward from the inner wall of the drum-section 15^c are a pair of parallel guide-rods 20, 20, which are slidably mounted in respective pairs of aligned, apertured, ears 21, 21 formed on the web 16. A pair of spaced apart, parallel links 22, 22, are pivoted on a lug 23 formed on the inner wall of said drum section, between the guide-rods 20, and a pair of parallel levers 24, 24 are pivoted at their inner ends on a lug 25 formed on the web 16, and near their middle are pivoted to the outer ends of the respective links 22, and are connected at their outer ends by a handle 26, said links and levers comprising an over-center toggle for moving the drum section 15^c radially inward and outward and locking it in either position.

For swinging the drum sections 15^b from and toward each other, when the drum-section 15^c is in its inner position, one of said sections 15^b has pivoted on its rear edge 100 face a lever 27 connected by a link 28 with the other hinged drum-section, the link and lever constituting an over-center toggle for locking the hinged drum-sections in either their innermost or outermost positions, a stop-pin 28^a on the link 28 being provided for stopping the lever 27 with the sections 15^b in opened out or operating position, as shown in Fig. 1.

For anchoring the leading ends of the 110

respective strips 13 on the drum 15 prior to rotating the latter, the drum-section 15^c is formed with a plurality of obliquely disposed apertures 29, 29 therethrough, intersecting the respective grooves 19 formed in its outer face, and an abutment 29^a, formed on the inner periphery of the drum at the inner ends of each of said apertures, is adapted to position the ends of the strips 10 inserted therein. Extending into each aperture 29 is the jaw or gripper end of a stop-pawl 30, adapted to coact with the wall of the aperture to bind the end portion of the strip 13 inserted in the aperture, as is clearly 15 shown in Fig. 2. The pawls 30 are pivotally mounted on a common rod 31, which is supported at its ends in inwardly projecting ears 32, 32 formed on the section 15^c at its front and rear ends. Each pawl 30 is provided with a projecting tongue spring 33, and the free ends of said springs rest upon a rod 34 also supported by the ears 32, said rod being positioned so as normally to hold the nose of each pawl yieldingly in work- 20 25 engaging position. Each pawl is formed with a tail-portion 30^b which rests in a transverse groove 35^a in a cam-rod 35, the latter being journaled at its respective ends in the ears 32, and provided with a knob 36 on its front end by which it may be manually rotated, simultaneously to disengage the pawls 30 from the work.

The drum 15 is adapted to be driven, in the direction indicated by the arrow in Fig. 35 1, by a motor 37 mounted on the base of the frame 10, through a reduction gear device 38, the latter including a sprocket 39, connected by a chain 40 with a sprocket 41 secured on the shaft 14. Between the motor 40 and the reduction gear device, the motor shaft is provided with a brake drum 42, and an electrically-actuated shunt solenoid brake 43, which may be of any suitable known construction, is associated therewith, for quickly 45 stopping the rotation of the drum 15 at the end of each winding operation, said brake and the motor being controlled by the timing mechanism mounted on the frame 11.

Said timing mechanism may be variously 50 constructed, but as here shown includes a switch-box 44 enclosing a starting switch adapted to be manually closed by means of a push-button 45, and a stop-switch adapted to be actuated by a plunger 46, the latter 55 being engaged by one arm of a small bell-crank lever 47, which is pivoted at its elbow on the switch-box 44, and has its other arm extending into the orbit of a circumferential series of spaced-apart, circumferentially- 60 adjustable studs or lugs 48, 48 mounted in arcuate slots in a rotatable disk 49.

The disk 49 is secured on a shaft 50 journaled on the frame 11, said shaft also having secured thereon a gear 51 adapted to 65 be driven through a train of gears 52, 53, 54,

and 55, the gear 55 being secured on a common shaft with a sprocket 56 connected by a chain 57 with a sprocket 58 on the rear end of the drum's shaft 14. Said disk 49 is thus adapted to be rotated whenever the apparatus is in operation and the spindle 14 is rotating, and said gears are of suitable relative sizes to produce such a speed reduction between said spindle and said disk that the distance between the respective studs 48 70 75 corresponds to the desired number of revolutions of the drum 15 for winding a particular ring. The disk 49, shaft 50, and gear 51 are preferably adapted to be removed as a unit, so that a similar assembly may be substituted for the winding of a different type of ring. The gear 52 is mounted on an adjustable lever 59 pivoted at the axis of the gear 53, so that said gear may be meshed with different sized gears 51, and also to permit relative angular adjustment of the disk 49 so as properly to position the studs 48 with relation to the angular position of the drum 15.

The auxiliary frame 12 comprises a stationary base member 12^a, and a movable member 12^b slidably mounted on suitable guides thereon. Said member 12^b is adapted to be adjusted toward or away from the frame 10, to position the strip-guiding and feeding means appropriately near to winding drums of different sizes which may be mounted alternatively upon the frame 10, a screw 60, for effecting such adjustment, being swiveled in a bearing 61 secured to the base member 12^a and threaded through an ear 62 extending downward from the bottom of the member 12^b, and provided with a hand-wheel 63.

The strip guiding and feeding means comprises a pair of parallel, horizontal rollers 64, 65 mounted on the frame 12^b, the upper roller 65 being journaled upon the offset portion 66^a of an eccentric shaft 66, said shaft being rotatably mounted in said frame member 12^b and provided at one end with a lever 67 by which it may be angularly adjusted to lower the roller 65 onto the roller 64 to clamp the strips 13 on occasion, the roller 65 normally being in raised position as shown in Fig. 1, with the lever 67 resting upon a stud 67^a projecting from the frame member 12^b, and the eccentric portion 66^a of the shaft 66 in over-center position.

When lowered onto the strips 13 and roller 64, as shown in Fig. 4, the weight and inertia of the roller 65 is sufficient to prevent recession or displacement of said strips when they are severed from the wound rings, there being relatively little backward pull thereon due to the tension of the strips. The shaft of the roller 64 is provided with a handwheel 68 by which said roller may be manually rotated to feed the strips 13 in unison, toward the drum 15, at the beginning of an 120 125 130

operation, to permit their ends to be inserted in the respective apertures 29 therein.

For guiding the strips to the rollers 64, 65, a plurality of vertical spaced-apart rollers such as 69 are mounted upon a bracket 70 secured at its ends to the walls of the frame 12^b, said rollers being adapted to act as side guides for the strips to aline them with the grooves 19 of the drum 15. A horizontal roller 70^a is journaled on the frame 12^b, at the work-receiving side of the guide rollers 69, to support the strips at a proper elevation as they pass between the side-guiding rollers 69.

15 For severing the wound rings 71, 71 from the unused portions of the continuous strips 13, a flat metal bar 72 may be inserted beneath said strips 13 and rested upon the drum 15 while the strips are cut against 20 said bar by means of a cold-chisel and hammer, as shown in Fig. 4.

To prevent separation of the convolutions of each ring 71, before it is provided with a cover or incorporated in a tire it is provided with a clamp or staple 73 which substantially encircles it transversely, the strip preferably being severed at such point that the ends of the winding slightly overreach each other, and the staple being applied at 30 such position as to engage both terminal portions of the winding. For applying such staples before the rings are removed from the drum, a stapling device 74 is adapted to be positioned upon the winding drum as shown in Fig. 5. Said stapling device comprises a horizontal beam-like member 74^a to one end of which is rigidly secured a vertical leg 74^b adapted to seat upon the surface of the drum as the device is placed in stapling position with relation to successive rings, to position the beam-like portion 74^a in substantially tangential relation to the drum. The opposite end of the portion 74^a is formed with a suitably shaped vertical aperture, in which is slidably mounted a plunger 74^c, urged upwardly by a spring 74^d, and formed with a head 74^e adapted to drive the staple 73 when the plunger is forced downward, as shown in Figs. 5 and 40 6, by the blow of a hammer 74^f (Fig. 5). The stapling device is provided with dowels 78, 78, for positioning the plunger with relation to the work.

For guiding the staples 73 and for crimping them onto the inner periphery of the rings 71, a hardened metal clinching or die plate 75 is inset into the drum 15, said plate being disposed transversely of the grooves 19, which continue through said plate, and 55 the latter is formed with staple-receiving recesses 76, 76, at the sides of said grooves. (See Fig. 6.) Each pair of said recesses is adapted to guide a U-shaped staple 73, radially with relation to the ring, and to turn 60 the end portions of the staple's legs toward

each other and onto the inner face of the ring to clinch them upon the latter. The plate 75 is formed with apertures 77, 77 between the grooves 19, to receive dowel pins 78, 78 projecting from the stapling machine 70 74, to position the latter.

A second plate 79, similar in all respects to the plate 75, is mounted in an adjacent portion of the drum 15, to permit the attachment of a second staple, as indicated at 80, 75 Fig. 7, if desired.

In the operation of my apparatus, the drum 15 being substantially in the position shown in Fig. 1, the roller 64 is manually rotated to feed the strips 13 toward the 80 drum, and their end portions are inserted into the respective apertures 29 therein, the same being automatically engaged and securely held by the gripper pawls 30. The roller 65 is then raised, thus releasing the 85 pressure on the strips 13, and the push-button 45 is pressed to start rotation of the drum 15, which winds the strips 13 into the respective grooves 19 of said drum. The rotation of the drum is automatically 90 stopped, after a determinate number of revolutions, by one of the studs 48 striking the bell-crank lever 47 and actuating the stop-switch within the switch-box 44, the stopping position of the drum being substantially as shown in Fig. 1, with the radially movable drum-section 15^c uppermost.

Next the bar 72 is inserted beneath the strips 13 adjacent the clinch plate 75, the roller 65 is lowered to clamp said strips 100 against the roller 64 to prevent their recession, after which said strips are successively severed, as by means of a chisel, as shown, the tackiness of the rubber coating on the strips 13, and the snug fit of the strips within the grooves 19 overcoming any tendency to unwind therefrom due to the stiffness of the strip material. Staples 73 are then attached to the respective rings 71 by means of the stapling device 74, after which the 110 drum is collapsed, as shown in Fig. 7, and the rings are removed therefrom. The drum is then restored to its annular form and the operation as described is repeated.

The apparatus is of especial advantage 115 where large production is required, its use resulting in a substantial saving of time and labor as compared with prior practices. The collapsible building-drum, avoiding the necessity of axially separable members for defining the winding grooves, provides for accurate alinement and gaging of the convolutions of the winding. The manner of 120 stapling the wound rings permits rapid production and provides a ring adapted to withstand handling prior to the application of a cover thereto or its incorporation in a tire.

Modifications may be resorted to within the scope of my invention, and I do not limit 125 my claims wholly to the specific form of 130

apparatus shown or to the exact procedure described.

I claim:

1. In apparatus for making endless rings, the combination of a rotatable drum formed with a plurality of individual work-receiving, circumferential grooves, and means for concurrently projecting forward to said drum in orderly relation the leading end 10 portions of a plurality of strips of ring-forming material.
2. Apparatus for making bead rings for tires, said apparatus comprising a collapsible drum formed with a plurality of individual, 15 work receiving, circumferential grooves in its outer face, means for rotating said drum, and a pair of feed rolls adapted to feed a set of continuous, bead-forming strips in orderly relation toward said drum and to prevent 20 recession of said strips and maintain them in orderly relation when portions of the strips, wound on the drum, are cut off.
3. In apparatus for making endless rings, the combination of a drum formed with a 25 circumferential groove, a pivoted, pawl-like clamp adapted to anchor one end of a strip of material within said groove, and means for rotating said drum.
4. In apparatus for making endless rings, the combination of a drum formed with a 30 circumferential groove, means for detachably securing one end of a strip of material within said groove, means for rotating said drum, and means for stopping said rotation after a determinate number of revolutions 35 thereof.
5. In apparatus for making endless rings, the combination of a drum formed with a plurality of circumferential grooves, clamping means associated with each of said 40 grooves for anchoring one end of a strip of material therein, means for rotating said drum to wind said material thereupon, and means for simultaneously releasing the several said clamping means. 45
6. Apparatus for making endless rings, said apparatus comprising a rotatable drum formed with a circumferential groove adapted to receive a plurality of convolutions of strip material, said groove having 50 its walls recessed to admit a binding staple for said material.

In witness whereof I have hereunto set my hand this 24th day of June, 1924.

CHARLES W. LEGUILLOON.
